(No Model.)

S. FOX.

UNDER FRAME FOR CARS.

No. 425,501.

Patented Apr. 15, 1890.

FIG. 2.

FIG. 3.

INVENTOR
SAMUEL FOX

Mr. E Craven, F. I. P. A.
24 Victoria Chambers, Leeds
William Sudder
Preston Street, Leeds.

UNITED STATES PATENT OFFICE.

SAMSON FOX, OF HARROGATE, COUNTY OF YORK, ENGLAND, ASSIGNOR TO
THE FOX SOLID PRESSED STEEL COMPANY, OF CHICAGO, ILLINOIS.

UNDER FRAME FOR CARS.

SPECIFICATION forming part of Letters Patent No. 425,501, dated April 15, 1890.

Application filed March 6, 1889. Serial No. 302,159. (No model.)

To all whom it may concern:

Be it known that I, SAMSON FOX, a subject of the Queen of Great Britain and Ireland, residing at Harrogate, in the county of York, 5 Kingdom of Great Britain and Ireland, have invented new and useful Improvements in the Manufacture and Construction of the Under Frames of Cars, such as are mounted upon bogies or otherwise for railway and 10 other rolling-stock, of which the following is a specification.

Under frames of cars being usually constructed of a combination of timber and metal are necessarily very heavy and costly, and 15 when of great length require to be strengthened by the addition of truss-rods and other devices to render them sufficiently rigid to bear the strains to which they are subjected, while at the same time such structures are 20 very costly.

Now my invention is in the manufacture of the component parts and in the construction of the under frames of cars such as are mounted upon bogies or otherwise and of the under 25 frames of railway and other rolling-stock generally, and has for its object the construction of the under frame-work of cars such as above referred to in such wise that the necessary strength and rigidity are obtained in a more 30 economical manner than heretofore usual. I attain these objects by constructing such under frame-work of pressed flanged metallic plates—such as mild steel—and as illustrated in the accompanying drawings, in which similar 35 letters represent similar parts throughout the several views.

Figure 1 is a longitudinal sectional elevation in part on the line 1 1 of Fig. 2, showing the side sills in two lengths and joined at the 40 flanges by rivets of under frame-work according to my invention. Fig. 2 is a plan, also in part. Fig. 3 is an end elevation. Fig. 4 is a transverse section at O O, Fig. 1. Fig. 5 is a transverse section at X X, the center 45 of the length of the frame-work.

A A are the side sills, shown to be flanged all round on the outside thereof, and being of greater depth in the middle than at the ends I am able to dispense with truss-bolts.

50 B is the head-stock, which, in conjunction with the parts C, D, H, and I, comprises the

end sill, of which there is one at each end of the frame-work.

H' H² are transoms between the two outside sills A A, with a part H³ in the center 55 for the reception of the king-bolt H⁴. Beneath the part H³, and attached to it and to the transoms H' and H², is the upper part of my improved central swivel-plate.

D' and F are intermediate transoms for 60 connecting the side sills A A at suitable distances apart.

E is a broad transom in the center of the length of the side sills A A—that is, at the junction of the two parts comprising each of 65 the said side sills. G is a similar transom to E (but narrower) at the bottom edge of and at the said junction of the respective side sills.

J J are longitudinal stays, and form 70 connections between the head-stocks or end sills B and the transoms H'.

K K K K are longitudinal stays connecting the transoms H² to the transoms F and the transoms F to transoms D'. 75

It will be obvious that the arrangement of the component parts of the under frame-work as hereinabove described may be varied to suit circumstances without departing from the nature of my invention. 80

What I claim is—

1. In the construction of railway and other rolling-stock, the combination, with the side sills, of the end sills, each consisting of the parts B, C, D, H, and I, flanged and secured 85 to each other and to the side sills, substantially as described.

2. In the construction of railway and other rolling-stock, the combination, with the side sills, of two transoms H' and H² and a part 90 H³ in the center for the reception of the king-bolt, all flanged and secured together substantially as described.

3. In the construction of railway and other rolling-stock, the combination, with the side 95 sills consisting each of two parts joined at the center, of a broad transom flanged and secured to the two parts comprising the side sills at their junction, substantially as described.

4. In the construction of railway and other rolling-stock, the combination, with the side

sills consisting each of two parts joined at the center, of a broad transom and a narrow transom, said transoms being flanged and secured to the top and bottom edges, respectively, of the parts comprising the sills at their junction, substantially as described.

5. In the construction of railway and other rolling-stock, the combination, with the side sills, of the end sills, the intermediate transoms, and the longitudinal stays connecting the intermediate transoms together and the

broad and narrow transoms at the center of the car, all flanged and secured together substantially as described.

Leeds, February 15, 1889.

SAMSON FOX.

In presence of—

THOS. E. CRAVEN,

F. I. P. A., Leeds.

WILLIAM SADLER,

Leeds.
